GOLF GAME

Joseph Hirschauer, Sioux City, Iowa, assignor of
one-twentieth to Hilda Mary Larson, Alta,
Iowa

Application June 11, 1934, Serial No. 729,947

2 Claims. (Cl. 273—32)

My invention relates to a golf game which can be used either indoors or outdoors and which is adapted to test the skill principally in driving.

An object of my invention is to provide a game which will readily indicate the accuracy and power of a golf ball when it is driven.

A further object of my invention is to provide the aforesaid objects in a game which is instructive as well as amusing.

10 A further object of my invention is the provision of such a device which is scientifically perfect and accurate and which will accomplish its results so that the skill of the golfer can be readily determined.

15 A further object of my invention is to provide means for indicating generally the length of a drive by means of tubular elements arranged to allow the centrifugal force imparted to the ball to be measured by means of suitable openings arranged in such elements.

20 A further object of my invention is to provide means for making the device completely accessible for repairs and the like.

25 A further object of my invention is to provide such a game of simple construction insofar as the objects are provided.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a side elevation of the device showing the driving opening in perspective,

Figure 2 is a side elevation showing the device adapted for outdoor use,

Figure 3 is a plan view of the device,

Figure 4 is an enlarged detail view of the receiving cup and indicating flags,

Figure 5 is a further plan view showing generally the arrangement of the openings,

Figure 6 is a side elevation illustrating the arrangement of the receiving openings,

45 Figure 7 is a detailed plan view of the receiving tube and flags, and

Figure 8 is an enlarged detail view of a section of the tubing showing the method of allowing release of the golf ball taken along the lines 8—8 of Figure 5.

The problem encountered in a device of this character is one of indicating the power and accuracy of a driven golf ball in a restricted space. For instance if this type of device were to be used 55 indoors, the space is restricted and yet it would

be essential to indicate just how far and how accurately a golf ball can be driven.

I will show that I have accomplished this by means of driving the ball up through a cone directly into a series of cylindrically arranged 5 and communicating tubes or pipes so that the accuracy of the shot and also the power will be readily determined.

I have used the reference character 10 to designate the cone-shaped member, into which the 10 ball is driven.

This member is approximately three feet in diameter at the opening 11 and tapers upwardly until it merges with the lower pipe member 1. (See Figures 1 and 3.) It will be seen that the 15 cone 10 merges practically tangent at the point of junction as shown in Figure 3. From this point upwardly the tubes 12 are arranged in a cylindrical form with the small spaces 13 between.

There are ten turns in the preferred form of 20 device of these tubes. I have found that a distance of approximately seventeen feet from the opening 11 to the junction of the cone of the tubes is suitable for this purpose and I have also found that a twelve foot diameter of the cylinder 25 is also suitable in this device.

In this way the ball will travel approximately 12 $\times$ pi or approximately thirty eight feet in each 30 complete turn, or in nine turns about three hundred forty two feet and correspondingly less for eight, seven, six, five and so forth turns. Of course the ball in this device will encounter no wind resistance although there will be some air resistance. In other words this system approximates the conditions involved in the regular 35 game of golf with the exception that the space is restricted and the ball travels circularly and upwardly.

The tubes are supported as in Figure 1, which 40 shows the indoor type of device, by means of the centrally positioned post 14, which tapers slightly upwardly until it terminates in the point 15, which carries the flag 16.

The post 14 receives the collar 17, to which is 45 attached the brace arms 18. These arms 18 are adapted to brace the steel straps 19, (see Figure 5) which can be arranged at 120° apart using three braces, or 90° using four.

The braces 19 are arranged so that each brace lies underneath one turn of pipe; in other words 50 these straps are inserted between the spaces 13.

To further strengthen the device, the braces 18 are secured to the vertical straps 20. (See Figure 6.) These straps are pinned or riveted fairly close to the inside of the periphery of the cylinder 55

so that the strain will be suitably supported. This structure need not be elaborated on since it does not form the essential part of the invention.

The member 14 is braced by means of the members 21 and 22 so that the entire device can rest upon the floor.

Where the device is used outdoors as shown in Figure 2, the post 14 can be inserted and anchored in the ground as at 22.

10 Each turn of the piping includes an opening to receive the golf ball after the ball has lost its forward momentum and starts to return. These openings are shown clearly in Figure 8. The tubing 12 in this case includes the opening 23.

15 It will be seen that this opening is made slightly past the vertical center line of the tube for reasons to be mentioned.

The opening 23 communicates with the tapered member 24.

20 At 23, the opening is made approximately twice the diameter of the golf ball, and at the opening 25 the diameter is made slightly larger, and just large enough to allow the ball to drop from this opening.

25 It will be seen that the opening 25 terminates the vertical portion 26.

The inside of the tubing 12 includes the opening 27. The tubing includes the backwardly bent flanges 28.

30 Around the inside of the tubing is arranged the strip 29, which is secured to the flanges 28 by means of suitable bolts 30. This strip is made in four foot sections so that individual sections can be removed so that the inside of the tube 12 can be inspected or repaired if desired.

35 It will now be seen (see Figure 8) that as the ball travels through the tubes 12, that the centrifugal force will tend to maintain the ball approximately in the position as shown in dotted lines as at 31. The faster the ball travels, the higher it will climb the slope 32.

40 As soon as the momentum of the ball is spent, it will stop and start to travel backwardly and downwardly through the pipes. Its speed will be greatly decreased and as soon as the ball comes to the opening 23, it will drop therein since this opening forms a slight indentation in the tube 12 and will then travel down through the member 24 through the vertical portion 26 and thence 45 through the opening 25.

45 It will be seen that as soon as the ball drops from the opening 25 that it will be accurately centered, and will drop with great speed to the indicating openings below, which will be explained later.

50 As explained previously, opening number one will be in the first or lowest layer of tubing, opening number two next and so forth.

55 (See Figure 5.) For instance if the ball travels only slightly beyond opening one, it will then return and fall through opening one. However a ball driven harder may pass slightly beyond opening two in the next layer of tubing and will then pass backwardly and through a similar element 24 attached to opening two. It will be seen that in this case the member 24 is made longer to correspond with the receiving cups or tubes arranged at the base of the device.

60 Similarly the tubes at openings 3, 5, 8, and 9 are also lengthened, although this is not really necessary since the main object is to keep the ends of the members 24 directly above the receiving cups.

65 The preferred form of course is to arrange the receiving cups as shown by the characters 33,

which shows the corresponding numerical value of the flag pertaining to that particular receiving cup or opening.

Of course it will be understood that the receiving openings 23 cannot be directly one above the other. In this way all of the tubular elements 24 would involve extreme lengths in some cases, so these elements are arranged in an approximately staggered relation in the tubing. For instance as shown, number one opening will be in the first or lowest layer of tubing, number two will be in the next layer slightly more than one turn, number three will be again slightly greater figuring from number two and so on. In this way the openings will lie in any suitable relation, preferably as shown in Figure 5. Where the elements 24 are of extreme length suitable braces can be supplied, although this may not be necessary since there is no strain on these elements.

As explained, an opening is positioned directly beneath the openings 25 of the elements 24. The reason for these openings is to indicate to the player just how accurately and how far his ball has been driven. (See Figure 4.) Each opening is indicated generally by the character 33. These openings are arranged vertically at the floor or ground level and are extended in tubular form until they pass to the central receiving tube 34. (See Figures 5 and 6.) In this way the central tube 34 receives the ball as it drops down into the receiving tube and can be carried to a suitable elevating mechanism, such as at 35, which is merely a chain belt with receiving fins 36 for carrying the balls upwardly.

50 Affixed at one side of the opening 33 is the slender wire or rod 37, which carries the thin metal flag 38. The rod 37 is pivoted at 39 to the lip 40, which can be bent from the cup.

A small spring 41 is secured to the inside of the tube. Adjacent the opening 33 is the narrow slotted portion 42 and the depression 43 for receiving the flag member.

55 The flag member in its normal position by virtue of gravity will rest as shown in the dotted lines in Figure 4. However as soon as the ball 45 45 strikes the horizontal extension of the rod, which is inside of the cup, the flag will be elevated to the position as shown in the solid lines in this figure.

60 The opening 33 is made about two inches in diameter to insure the ball dropping therein in case of any small variations.

65 Of course it will be understood that the upper openings will be positioned accurately above these openings and due to the speed that the ball will travel in dropping from its elevated height, it will always drop accurately within the openings and the flag will be raised as shown for a short interval.

65 The spring 41 will then act to thrust the lower end of the rod 37 outwardly. This thrust will be just enough to throw the rod off center, and the flag will then drop to the position as shown in dotted lines by gravity.

70 As soon as the flag rises, the player will readily see just how accurate and how powerful his shot was, since the openings 33 will individually receive the ball rising to that particular level.

75 A study of Figure 6 will indicate the factors entering into the success of the golf ball in rising to the corresponding levels and openings. For instance if the ball were driven accurately, it will follow the direction indicated by the arrows 75

46; in other words the ball will follow the axis of the cone 10.

If the ball is not driven hard enough, it will probably rise to the openings in level 6 or 7 5 or approximately to this point. However if the ball is accurately and also powerfully driven, it will probably rise to level 9 or possibly to the upper level 10, which of course has no opening. The upper level 10 can be stopped up at the end 10 if desired, although this is not necessary.

If the ball however takes the direction as indicated by the arrows 47 in Figure 6, the ball will tend to bounce along the inside of the cone and will be retarded greatly by this action and as a 15 result will probably only go up to one of the first three levels and thereabouts.

In this way the speed and also the accuracy 20 of the shot will be determined. The cone 10 can be positioned to lie at an angle from the ground, 20 which angle will be the proper angle in which the usual golf ball should be driven to secure the best effects of range and accuracy.

All of the factors entering into the accurate 25 flight of the golf ball from the driving tee are taken into account in this device, and the relative values are then obtained.

As long as the ball travels at a fair rate of speed, it will travel along the tubing 12 approximately as shown in 31 of Figure 8, and as heretofore explained as soon as its momentum is spent, 30 will roll backwardly slowly and drop through the opening.

I have also provided the wire netting 48 in 35 case the golf ball strikes outside of the opening 11, which will cause it to be returned to the driving tee.

The receiving tubes and flag receiving receptacle include the flanges 49 if desired.

It will now be seen that I have provided a golf 40 game which can be used in a limited space, either indoor or outdoor, which will readily indicate the accuracy or power of a golf ball drive.

It will also be seen that I have provided means 45 in this game which will provide amusement as well as instruction.

It will also be seen that this device operates on well known scientific principles, which will permit of great accuracy, and it will be seen that the device is constructed simply, is access-

ible for repair and the like and is of comparatively simple construction.

Some changes may be made in the construction and arrangement of the parts of my invention without departing from the real spirit and purpose of my invention, and it is my intention to cover by my claims any modified forms of structure or use of mechanical equivalents, which may be reasonably included within their scope. 5

I claim as my invention:

1. A golf game comprising a cone member positioned to receive a driven golf ball, a cylindrically arranged coil of round pipes communicating with the cone member, means for indicating the extent of travel of the golf ball in the coil of 15 pipes, said means including openings arranged at separate horizontally spaced intervals in the coil, further means for registering the drive including a plurality of cups including pivoted flags adapted to receive the golf balls dropping through said 20 openings, means for accurately centering the balls above said cups including tapered necks communicating with the pipes, said necks including vertical portions positioned directly above the receiving cups, said cups being arranged in a 25 flat horizontal plane beneath said coils to correspond with said openings.

2. A golf game comprising a cone member positioned to receive a driven golf ball, a cylindrically arranged coil of round pipes communicating 30 with the cone member, means for indicating the extent of travel of the golf ball in the coil of pipes, said means including openings arranged at separate horizontally spaced intervals in the coil, further means for registering the drive including a plurality of cups including pivoted flags adapted to receive the golf balls dropping through said 35 openings, means for accurately centering the balls above said cups including tapered necks communicating with the pipes, 40 said necks including vertical portions positioned directly above the receiving cups, said cups being arranged in a flat horizontal plane beneath said coils to correspond with said openings, means for returning the driven golf balls including a 45 central tube communicating with the receiving cups with tributary tubes.

JOSEPH HIRSCHAUER.
